UNITED STATES PATENT OFFICE

RALPH E. HYDE, OF CLEVELAND, OHIO, ASSIGNOR TO THE OSTER MANUFACTURING COMPANY, OF CLEVELAND, OHIO, A CORPORATION OF OHIO

DIESTOCK

Application filed February 18, 1928. Serial No. 255,287.

The present invention relates, as indicated, to a die stock, and more particularly to a die stock of the general type disclosed in the patent to Oster No. 1,044,808. It is an object of the present invention to provide a die stock of the character described having various improved features making for increased accuracy, safety and efficiency in the use thereof. Further objects of the invention will appear as the description proceeds. To the accomplishment of the foregoing and related ends, said invention, then, consists of the means hereinafter fully described and particularly pointed out in the claims.

15. The annexed drawing and the following description set forth in detail certain mechanism embodying the invention, such disclosed means constituting, however, but one of various mechanical forms in which the principle 20 of the invention may be used.

In said annexed drawing:

Fig. 1 is a front elevation of a stock of the type contemplated by the present invention; Fig. 2 is a bottom plan view thereof; Fig. 3 25 is a transverse section taken substantially on the line 3—3 of Fig. 1; Fig. 4 is a rear elevation of said die stock; and Figs. 5 and 6 are detail sectional views upon an enlarged scale.

20. Referring more particularly to the drawings, the reference numeral 1 indicates the back plate of a die stock, while the numeral 2 indicates the front plate thereof. Said back plate is formed with a bore 3 bounded by 25 a rearwardly extending annular flange 4, and said front plate is formed with a corresponding aperture 5. The dies 6 extend into side bore 5. The bore 5 is slightly enlarged adjacent its outer end as at 7, and an annular 40 groove 8 of considerably greater depth circumscribes said bore, forming an outstanding flange 9 between said enlarged bore 7 and said groove 8. A second narrower flange 10 forms the outer surface of said front plate 2.

45. Journalled upon said flange 9, resting upon said flange 10, and provided with cam elements 11 extending into said groove 8 and engaging said dies 6, there is a cam plate 11, the bore 12 of which snugly fits the external 50 diameter of said flange 9. Said bore 12 is

slightly enlarged adjacent its outer end as at 13. A cam plate washer 14 is provided with an externally threaded cylindrical flange for engagement with the threads in the portion 7 of the bore 5, and with an annular flange 16 overlying the outer end of the flange 9 and entering the enlarged portion 13 of the bore 12 of the cam plate 11. The bore 15 of said cam plate washer 14 has a diameter corresponding to that of the bore 5. The cam plate washer 14 is locked in place by means of a pin 17 extending through an aperture in the flange 16 thereof and into an aperture in the flange 9.

55. Said cam plate 11 is provided with a laterally extending ear 18 formed with an arcuate groove 19 in which there is mounted a pin 20. Said pin is adjustable longitudinally of said slot 19, and is adapted to be clamped in adjusted position by means of clamping 60 plates 21 and 22 abutting against opposite faces of said ear 18, said plate 22 being provided with a handle 23 for convenience of operation. Mounted upon a depending projection 24 on the front plate 2 are a pair of 65 bearings 25 adapted to form journals for a pivot pin 26 upon which is mounted an operating member 27 having a handle 28 projecting therefrom. A cam groove 29 is formed in the external surface of said operating member 27, and the inner end 30 of said pin 20 is entered in said groove 29. Substantially hemispherical depressions 31 and 32 are formed in the opposite ends of said groove 75 and the portion 52 of said groove in which 30 is formed the depression 31 has its axis disposed in a plane normal to the axis of said member 27 for a purpose to be explained.

80. The inner end 30 of said pin 20 is provided with an axially extending recess 33 in 75 which is mounted a round ended latch member 34 which is urged outwardly by a compression spring 35 enclosed within said recess 33.

85. The back plate 1 and front plate 2 of the die stock are integrally connected by a pair of diametrically opposed relatively narrow webs 36 defining between them relatively large openings 37 through which access may be had to work held in said die stock. A plurality 90

(preferably three) of work centering jaws 38 are reciprocably mounted in guide-ways 39 in said back plate 1, said jaws extending into the bore 3 thereof and being formed with teeth 40 for cooperation with the threads 41 of a scroll plate 42. Said scroll plate is journalled on the flange 4 and is provided with a handle 43 for convenience of operation. A relatively wide circumferential groove 44 is formed in said flange 4 adjacent the outer end thereof, and a washer 45 backs said scroll plate 42, said washer slightly overhanging said groove 44 as indicated at 46 in Fig. 6. A split spring ring 47 having one end 48 thereof bent to enter an aperture 49 adjacent the periphery of said washer 45 retains said washer and said scroll plate 42 in position. As is clearly shown in Figs. 5 and 6, said ring 47 is formed of stock having a cross-sectional diameter slightly less than that of the groove 44. It will be seen that the described arrangement and construction of parts causes the ring 47 to exert a pressure toward the left as viewed in Figs. 3, 5, and 6 upon the washer 45 and the scroll plate 42. Such pressure is the resultant of the contractile tendency of the ring 47 operating against the concave side wall of the groove 44, the washer 45 being of such thickness as to prevent the ring 47 from reaching the bottom of the groove 44.

Sockets 50 are formed on or secured to the webs 36, said sockets being adapted to receive handle members 51 for rotating said stock.

While the operation of the device is believed to be clear from the above description, a brief summary thereof may be given here. Initially, the handle 23 is rotated in a counterclockwise direction to release the clamping engagement of the plates 21, 22, upon the ear 18 and permit the adjustment of the cam plate 11. The handle 28 is then rotated in a clockwise direction as viewed in Fig. 3 to position the end 30 of the pin 20 in the portion 52 of the slot 29. Thereafter, the cam plate 11 is rotated to set the chasers to the proper size for cutting upon the piece of work in question, and then the handle 23 is rotated in a clockwise direction to lock the cam plate in adjusted position with respect to the pin 20. The cam plate 11 and the cam plate washer 14 will, as usual, have indicia thereon to facilitate such setting.

Thereupon a piece of work to be threaded is inserted through the bores, 3, 5, and 15, and the operator grasps the handle 43 to rotate the scroll plate 42. Rotation of said plate causes the teeth 40 of the jaws 38 to follow the spiral 41 of the scroll plate, whereby said jaws 38 are uniformly set up toward the center of the bore 3 to center the work in said bore. The operator then grasps the handles 51 and rotates the whole stock with respect to the work to cut the desired thread.

In order, now, to remove the stock from the work without backing it off along the thread just cut, the operator grasps the handle 28 and rotates the operating member 27 in a counterclockwise direction to the position shown in Fig. 3. Such rotation causes the pin 20 to follow the cam groove 29 toward the left as viewed in Fig. 2, and, since the pin is rigidly clamped to the ear 18, such movement of the pin causes rotation of the cam plate 11 in a clockwise direction as viewed in Fig. 1. Such rotation is sufficient to release the engagement of the dies 6 with the work and to permit the removal of the stock without backing the same off along the thread.

It will be quite apparent that the length of the slot 19 determines the range of adjustment through which the cam plate may be rotated in working upon different sizes of pipe or bar stock. When the handle 28 is in the position illustrated in Fig. 3, the latch member 34 lies in the depression 32 to prevent accidental movement of the operating member 28, and similarly when the latter has been moved to its opposite extreme position, the latch member 34 will lie in the depression 31 for the same purpose. Furthermore, the pin lies within the circumferential portion 52 of the groove 29, and cannot be jarred toward the left as seen in Fig. 2 because of its bearing on the side walls of said portion 52. It will be apparent that, once the pin 20 has been positioned for a particular size of work, all necessary movement of the cam plate will be effected by operation of the member 27 and without the necessity of varying the adjustment of the pin 20 in the slot 19.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. The combination with a die-stock carrying cutters, of a cam plate for advancing and retracting said cutters rotatably mounted on said die-stock and having a lateral ear formed with an arcuate slot therethrough, a pin extending through said slot, means to secure said pin in any adjusted position in said slot, an operating member on said stock, said operating member being formed with a cam groove, and said pin extending into said cam groove, and cooperating means carried by said pin and said member for preventing accidental shifting of the latter.

2. The combination with a die-stock carrying cutters, of a cam plate for advancing and retracting said cutters rotatably mounted on said die-stock and having a lateral ear formed with an arcuate slot therethrough, a pin extending through said slot, means to secure

5 said pin in any adjusted position in said slot, an operating member on said stock, said operating member being formed with a cam groove, and said pin extending into said cam groove, said groove being formed with a recess adjacent each end thereof, said pin being provided with a recess in that end which enters said groove, a latch member in said pin recess and adapted to enter selectively said slot recesses, and a spring within said pin recess urging said latch member outwardly.

10 3. The combination with a die-stock carrying cutters, of a cam plate for advancing and retracting said cutters rotatably mounted on said die stock, a cam rotatably mounted on said die stock on an axis parallel to the plane of said cam plate, and a pin carried by said plate and cooperably engaging said cam.

15 4. The combination with a die-stock carrying cutters, of a cam plate for advancing and retracting said cutters rotatably mounted on said die stock, a cam rotatably mounted on an axis parallel to the plane of said cam plate, and a pin releasably secured to said cam plate 25 and projecting therefrom in a direction normal to the plane of said cam plate, the free end of said pin cooperatively engaging said cam.

20 5. The combination with a die-stock carrying cutters, of a cam plate for advancing and retracting said cutters rotatably mounted on said die-stock and having a lateral ear formed with an arcuate slot therethrough, a pin extending through said slot releasably engaging 25 said plate, means on said stock adjacent said cam plate ear providing bearings for a pivot, a pivot mounted in said bearings in parallelism with the plane of said cam plate, and a cylindrical operating member axially journaled on said pivot and provided in its cylindrical surface with a cam groove, said pin extending into said groove.

40 6. The combination with a die-stock carrying cutters, of a cam plate for advancing and retracting said cutters rotatably mounted on said die-stock and having a lateral ear formed with an arcuate slot therethrough, a pin extending through said slot releasably engaging said plate, means on said stock adjacent said cam plate ear providing bearings for a pivot, a pivot mounted in said bearings in parallelism with the plane of said cam plate, a cylindrical operating member axially journaled on said pivot and provided in its cylindrical 55 surface with a cam groove, said pin extending into said groove, and cooperating means carried by said pin and said operating member for preventing accidental shifting of the latter.

60 7. The combination with a die-stock carrying cutters, of a cam plate for advancing and retracting said cutters rotatably mounted on said die-stock and having a lateral ear formed with an arcuate slot therethrough, a pin extending through said slot releasably engaging

70 said plate, means on said stock adjacent said cam plate ear providing bearings for a pivot, a pivot mounted in said bearings in parallelism with the plane of said cam plate, and a cylindrical operating member axially journaled on said pivot and provided in its cylindrical surface with a spiral groove receiving a portion of said pin, said spiral groove opening into a short circumferential groove.

Signed by me this 15th day of February, 75
1928.
